E. E. THIEL

PRINTING PLATE HOLDER

Filed August 22, 1924

INVENTOR:
EMIL E. THIEL

BY Allen Allen

ATTORNEYS.

UNITED STATES PATENT OFFICE.

EMIL E. THIEL, OF CINCINNATI, OHIO, ASSIGNOR TO THE PRINTING MACHINERY COMPANY, OF CINCINNATI, OHIO, A CORPORATION OF OHIO.

PRINTING-PLATE HOLDER.

Application filed August 22, 1924. Serial No. 723,644.

To all whom it may concern:

Be it known that I, EMIL E. THIEL, a citizen of the United States, and a resident of Cincinnati, in the county of Hamilton and State of Ohio, have invented certain new and useful Improvements in Printing-Plate Holders, of which the following is a full, clear, and exact description, reference being had to the accompanying drawing, 10 forming part of this specification.

My invention relates to devices adapted for use with a bed, for retaining printing plates and the like thereon. It further relates more particularly to such devices 15 where used with printing plate beds having numerous holes therein, into which the devices of my invention are dropped.

"Drop-in hooks" as such devices are termed commercially, usually comprise a 20 jaw, and a holder, the latter being adapted for dropping into the holes or channels in a printing plate bed, and some kind of means resulting in the operator being able to adjust the position of the parts so as to bring 25 the jaw up against a printing plate thereby holding the plate down on the bed, and also holding it against displacement in the plane of the bed.

It is the object of my invention to provide 30 a carrier which has a firm foundation, and snug fit to the bed hole in which it is placed, with spring elements for holding it in place against dislodgment.

It is my object to provide for a simple 35 mode of assembling the springs with the carrier and retracting the springs when the carrier is to be removed.

It is also my object to provide for a double support for the jaw element in the 40 carrier, designed to give a very strong and even action to the jaw, and a line of application of force to the jaw which assures a firm and non-chattering engagement with the plate.

45 I accomplish my object by that certain construction and arrangement of parts to be hereinafter more specifically pointed out and claimed.

In the drawing:

50 Figure 1 is a top plan view of one of the devices.

Figure 2 is a side elevation of the device, when in place in the bed of a press or the like.

Figure 3 is a front elevation of the holder 55 complete.

Figure 4 is a section on the line 4—4 of Figure 3.

Figure 5 is a perspective of the carrier.

The bed of a press is indicated at 1 having 60 holes 2 therein for the reception of the "drop-in hooks." The holes are enlarged at 3 near the base thereof, to provide shoulders for engagement with the spring hold-down 65 devices of the carrier.

The carrier is formed with a base 4, which is curved, front and back to engage snugly but slidably in the hole in the press bed. With a different shape of hole, the base 70 would be formed to fit such hole as happened to be used. There are uprights 5 on the base interspaced for the reception of the stem portions of the jaw and between which the jaw stem will fit snugly but movably. 75

The uprights are formed with holes 6 for reception of a pivot pin 6^a for the pivoted bearing block, and with holes 7 for reception of the pivot pin 7^a for the legs of the jaw 80 stem.

At the tops the uprights are formed with a channel 8 on each side having a beveled wall 8^a, as a base and a kerf 9 is made at the tops of the uprights, intersecting the upper 85 ends of the channels.

The hold-down springs are formed with T-heads 10 to seat in the said kerfs, bodies 11 which extend down through the channels, and thence along the sides of the uprights, and turned-out ends 12, which engage under 90 the shoulders on the holes of the bed.

The lateral width of the carrier is such that when the two springs are forced closely against the sides of the carrier, the latter can then be dropped down through the 95 selected hole in the bed. When the springs have been started down, they are released by the operator, and their ends 12 will snap under the shoulders, when the carrier has been thrust down so as to be level with the 100 top of the bed.

To remove the carrier, a tool having two blades is thrust between the sides of the uprights and the wall of the hole in which the carrier is located, guided by the channels 105 in the top of the sides of the carrier, and by this means, the spring brought close to the sides again, whereupon they are freed

from the shoulder at the base of the bed hole, and the carrier may be lifted out. The jaw 13 is of usual type and has a stem formed to fit within the uprights of the carrier. One portion of the stem as at 14 extends down to receive the pivot pin 7^a, and the other portion of the stem has a threaded socket 15 for the screw 16. There is a hole 17 extending down through the top 10 of the jaw to permit a tool to be inserted for engaging the squared socket 18 in the head of the screw. The screw has a special button-like head 19, which engages in a socket 20 formed in the pivot bearing block 21. This block is mounted between the uprights by means of the pin 6^a.

As so constructed the holder is dropped into a press bed hole, with the jaw facing the plate to be held in place. The operator 20 then inserts a tool and turns the screw, which forces the jaw toward the printing plate.

As the screw passes down through the jaw stem, and tilts the jaw, the bearing block swings on its pivot pin, thereby assuring a firm bearing for the jaw, and imparting thrust thereto on a line which will tend to hold the carrier firmly in place against what may be termed the back wall 30 of the hole into which it was dropped.

Having thus described my invention, what I claim as new and desire to secure by Letters Patent, is:—

1. A holding device for printing plates 35 comprising a jaw and a carrier, means for movably mounting the jaw in the carrier, said carrier having spring tongues mounted to extend down along the sides thereof, said tongues turned outwardly at the free ends 40 thereof to act as hold-down devices.

2. A holding device for printing plates

comprising a jaw and a carrier having bottom and sides, means for movably mounting the jaw in the carrier, said carrier having kerfs in the top thereof, spring having 45 T-ends set in said kerfs, and extending downwardly along the sides of the carrier, and having turned-out ends adapted to pass down through a press bed, when forced against the sides of the carrier, and to 50 spring out into engagement with the press bed, when the carrier is thrust home into such bed.

3. In a device of the character described the combination with a holder, a jaw, means 55 for movably mounting the jaw in the holder, an adjusting screw movable lengthwise through the jaw having an extended end, and a pivoted element in the carrier, having an aperture adapted to receive the end 60 of the screw, for the purpose described.

4. In a device of the character described the combination with a holder, a jaw, means for movably mounting the jaw in the holder, an adjusting screw movable lengthwise 65 through the jaw having an extended end, and a pivoted element in the carrier, having an aperture adapted to receive the end of the screw, for the purpose described, 70 said screw and pivoted element having head and socket engagement between each other.

5. In a device of the character described the combination with a holder having base and sides, a jaw having a stem, held on a pivot pin between the sides, a screw mounted 75 in the stem, and moving lengthwise thereof, and a bearing block pivoted in said holder, against which said screw thrusts when turned within the stem, for the purpose described.

EMIL E. THIEL.
